B. G. DOLL.

HOT WATER HEATER.

APPLICATION FILED JAN. 19, 1912.

1,075,700.

Patented Oct. 14, 1913.

UNITED STATES PATENT OFFICE.

BENJAMIN G. DOLL, OF LANCASTER, PENNSYLVANIA.

HOT-WATER HEATER.

1,075,700.

Specification of Letters Patent. Patented Oct. 14, 1913.

Application filed January 19, 1912. Serial No. 672,118.

To all whom it may concern:

Be it known that I, BENJAMIN G. DOLL, a citizen of the United States, residing at Lancaster, in the county of Lancaster and State of Pennsylvania, have invented certain new and useful Improvements in Hot-Water Heaters, of which the following is a specification, reference being had therein to the accompanying drawing.

10 This invention relates to a hot water heater for buildings, and relates more particularly to means whereby each radiator or heating coil is controlled and supplied from the heater in a separate manner.

15 The practice has been to use a common boiler for the entire system of distribution, so that if the boiler fails to perform its work, the entire heating system was thrown out and the cutting out of one radiator to 20 the relief of the other was an impossibility, the result being that if a flow was to one floor and radiator, the other floors and radiators would not receive the full supply of the hot water.

25 The object of the invention is to provide a heater that shall be cheap, durable, efficient, and so constructed that renewals of parts may be readily effected.

Another object of the invention is to provide means whereby the water to supply each radiator is heated in a separate manner.

Still another object is to provide a heater that will supply hot water to a radiator or 35 coil situated on a lower plane than that of the heater, as in the case of a sub-cellar.

With these and other objects in view, my invention consists in certain construction and combination of parts as will herein- 40 after be described and claimed in the annexed specification, and illustrated in the accompanying drawings which form a part of this application, and in which like figures of reference refer to corresponding parts 45 in all of the views; but it is fully understood that while I have here described my invention as shown, that I do not confine myself to the exact design, as slight changes may be made in the construction and ar- 50 rangement of the several parts without departing from the spirit of the invention.

In the drawings:—Figure 1, is a partial view of a heater shown in perspective, with the side cut away to expose my device. Fig. 55 2, is a vertical sectional view of the same. Fig. 3, is a horizontal sectional view of one

of the diaphragms. Fig. 4, is a cross-sectional view of the main water chamber.

Referring to the drawings:—1, indicates the usual walls of a furnace forming a combustion chamber 2, within the lower part of which are the grates 3. Within said combustion chamber 2, and surrounding three sides of the grate 3, is placed a main water heating chamber 4, composed of a casting 60 7, which is U-shaped in cross-section and formed with a flange 5, to which are secured the fire wall plates 6. The upper surface of said casting 7, is provided with a series of vertical pipes 8, communicating 65 with the chamber 4, therein; each of said vertical pipes 8, being in two parts and connected by a union 9.

Mounted in a vertical transverse position 75 within the chamber 4, and supported upon the upper ends of the pipes 8, to which they are secured by the fitting 10, are the water heating diaphragms which are composed of the parts 11, and 12; the part 11, being provided with a flange 13, to which the part 12, 80 is secured, thus forming a compartment 14, capable of holding a thin sheet of water. The upper end of said diaphragm chamber 14, is connected to a flow-pipe 15, which 85 supplies an individual radiator or coil 16, 90 the return pipe 17, from which enters a header 18, which is connected to the rear end of the casting 7; thus returning the water to the main chamber 4. It will thus be seen that there is one diaphragm provided for 95 each radiator or coil to which it is connected by an individual flow pipe, and as the diaphragm is placed in the combustion chamber directly over the fire and as the water passing therethrough is in a thin sheet, it 100 is heated in an almost instantaneous manner and rendered very hot with a small amount of fire, thus sending it to a coil or radiator in any part of the building, either above or below the plane of the 100 heater; and furthermore, any radiator or coil may be cut out without affecting the remaining ones.

It is, of course, understood that the valves 19, which control the coils are so constructed as to provide a sufficient leak to prevent trouble caused by steam forming in the dia- 105 phragm.

Having thus described my invention what I claim as new and desire to secure by Letters Patent is:—

In a hot water heater of the class de-

scribed, the combination with a furnace having a combustion chamber, of a main water heating compartment arranged in said furnace, said main water heating compartment being U shaped in cross-section and a multiple of water heating chambers mounted in said combustion chamber, above the fire and transversely to the main water heating compartment, each of said chambers independ-

ently connected to said water heating compartment.

In testimony whereof I affix my signature in presence of two witnesses.

BENJAMIN G. DOLL.
